UNITED STATES PATENT OFFICE.

WALTER C. POLLARD, OF STEELTON, PENNSYLVANIA.

MOPPING MACHINE.

Application filed May 3, 1922. Serial No. 558,136.

To all whom it may concern:

Be it known that I, WALTER C. POLLARD, a citizen of the United States of America, and resident of Steelton, in the county of 5 Dauphin and State of Pennsylvania, have invented certain new and useful Improvements in Mopping Machines, of which the following is a specification.

This invention relates to floor washing or 10 mopping machines, and has for an object the provision of a machine which employs an endless mopping element such as a web of fabric, associated with means by which the web is moved with relation to the surface being treated, while at the same time, 15 an apparatus including the web and its driving mechanism is pushed or pulled over the surface being treated.

It is a further object of this invention to 20 produce a scrubbing machine of the character indicated in which the mop is supplied with fluid at or about its point of contact with the surface to be scrubbed, the said device also including novel means for 25 pressing or wringing moisture from the mop in its travel, and means for collecting the water dislodged from the mop in order that it may be discharged from the interior of the mechanism.

It is a still further object of this invention 30 to produce means by which the mop is given a vibratory or uneven movement as it is being driven; and furthermore the provision of novel means for increasing or 35 diminishing the tension of the mopping element, according to the requirements in practice.

A still further object of this invention is 40 to provide novel means for operating the driven parts of the machine in order that the mop may be constructed to travel with relation to the carrier and its operating mechanism.

With the foregoing and other objects in 45 view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation

of a scrubbing machine embodying the invention;

Figure 2 illustrates a similar view of the opposite side thereof;

Figure 3 illustrates a plan view of a fragment of the handle and driving shaft;

Figure 4 illustrates a longitudinal sectional view of the machine;

Figure 5 illustrates a top plan view thereof; and

Figure 6 illustrates a transverse sectional view thereof on a line corresponding with the line 6—6 of Fig. 4.

In these drawings 10 denotes a casing which is open at the bottom and in the sides of which a plurality of guiding rollers 11 are rotatably mounted and in engagement with which the mopping element 12 is threaded in order that the said mopping element will be guided by the rollers so that it will travel 70 in a circuitous path, as will presently appear. The mopping element 12 may consist of an endless web of fabric appropriate for the purpose, and the inventor does not wish to be limited with respect to the material. 80 The said element 12 will hereafter be referred to as a "mop."

The wringing rolls 13 are journaled in proximity to each other, the space between the wringing rolls being sufficient to permit the passage of the mop when the said mop is under compression or under the pressure of the wringing rolls, the upper of said wringing rolls being pressed downwardly by springs such as 14 that are interposed between the top of the casing and the bearings of the wringing rolls, as will be understood by one skilled in the art.

As illustrated in Fig. 4, the mop is guided upwardly from the lower edge of the casing 95 longitudinally thereof, and then downwardly to the lower edge of the casing again at a point between the ends of the casing. A spraying pipe 15 extends transversely of the casing above one of the lowermost rollers 100 which the mop engages, and at this point water is supplied to the mop and to the surface being scrubbed.

The means for moving the mop, in the present embodiment of the invention, comprises two driving shafts 16 which are angular in cross section between their journals, it being understood that their journaled ends are rotatably mounted in appropriate way in the sides of the frame. The journals project 110

- from one side of the frame and they carry pulleys 17 that are connected by a belt 16'. One of the journals is provided with a pulley 19 to engage a belt 20 which extends to a pulley 21 on the drive shaft 22, which drive shaft may be rotated by a crank 30 or by a motor connected to the pulley 31 on the said drive shaft, it being understood that the said drive shaft is journaled in a handle 32 by which the mopping machine may be forced or pulled over the surface being treated. The belt 20 operates over a pulley 21 on the drive shaft and by this means the scrubbing mechanism is driven.
- 15 The upper wringing roll is rotated by a pulley 34 to which a belt 35 is connected, the said belt 35 operating over a pulley 36 on the journal of one of the shafts 16 so that by the means just stated, the wringing rolls are constantly driven and this driving augments the movement of the mop.
- 20 In the interests of aiding the drive of the mop, one of the rollers 11 may be provided with a pulley 37 which is driven from one of the shafts 16 by a belt 38 and, of course, if necessary other rollers could be provided with power applying mechanism to facilitate the movement of the mop.
- 25 A tensioning element engages the mop, and in the present embodiment of the invention, it comprises an arm 39 mounted on a pivot 40, the said arm carrying an idle roller 41 which bears against the mop, as fully shown in Fig. 4. A tank or receptacle 42 is stationary in the casing under the wringing rolls for the purpose of catching the drippings from the mop, and this tank has a discharge spout 42' leading to the exterior of the frame and provided with a suitable valve 43. The tank 44 for supplying water is ex-

teriorly arranged on the frame and the pipe 15 connects with it. Communication between the tank and the pipe 15 may be controlled by a valve 46.

Two of the bottom rollers 11 may have 45 caster wheels 45 applied to their ends beyond the casing, the said caster wheels serving to reduce friction while the apparatus is being moved over the surface being treated, and this arrangement of parts will also serve to 50 facilitate or augment the driving action by which the mop is moved. The peripheries of the bottom rollers over which the mop travels must, of course, be in such relation to the caster wheels as to cause the mop to 55 engage the surface being scrubbed or treated, as will be understood by one skilled in the art.

As a description of the functions of the several parts of the apparatus has been 60 given in connection with a description of the parts, the disclosure is believed to be sufficiently clear to enable one skilled in the art to practice the invention.

I claim:

65 In a mopping machine, a casing, guiding rollers journaled therein, a mop threaded in engagement with the rollers, mop moving means comprising shafts angular in cross section engaging the said mop, means for 70 tensioning the mop to increase the frictional contact of the mop with the said shafts, means for rotating the shafts, wringing rollers between which the mop travels, a receptacle for fluid expelled from the mop, 75 means for supplying water to the mop, and means for driving certain of the rollers which the mop engages.

WALTER C. POLLARD.
